UNITED STATES PATENT OFFICE.

JOHN W. BINGAMAN, OF ABERDEEN, OHIO.

FEATHER-RENOVATOR.

SPECIFICATION forming part of Letters Patent No. 258,979, dated June 6, 1882.

Application filed February 3, 1882. (No model.)

To all whom it may concern:

Be it known that I, JOHN W. BINGAMAN, of the town of Aberdeen, county of Brown, and State of Ohio, have invented certain new and useful Improvements in Apparatus for Renovating Feathers, &c., of which the following is a specification:

The object of my said invention is to produce an apparatus for renovating feathers, &c., in which the steaming of one lot and the drying of another shall be simultaneous. This is accomplished by the use of a sliding partition which divides the chamber into two portions, one of which is subjected to steam heat and the other of which receives the steam itself, as will hereinafter be more specifically explained.

Referring to the accompanying drawings, which are made a part hereof, and on which similar letters of reference indicate similar parts, Figure 1 is a side elevation of apparatus embodying my invention; Fig. 2, a longitudinal vertical section thereof on the dotted line *xx*; Fig. 3, a horizontal section of the steaming-chamber, looking downwardly from the dotted line *yy*; and Fig. 4, a transverse vertical section, looking to the right from the dotted line *zz*.

In said drawings, the portions marked *A* represent the boiler used with my improved apparatus; *B*, a steam-pipe leading therefrom; *C*, a steam box or space occupying the bottom of the chamber; *D*, a pipe leading therefrom; *E E*, perforated pipes connected with the pipe *D*; *F*, a sliding partition dividing the structure into two portions or chambers; *G H*, said chambers, and *I J K* doors thereto.

The boiler *A* may be of any approved form wherein steam can be generated. As high pressure is not desired, it may be of sheet metal. For a similar reason an open funnel, *A'*, may be used to introduce water into said boiler, the lower end of the funnel extending down considerably below the surface of the water in the boiler, so that steam will be prevented from escaping through it. The usual fire-place and smoke-stack are of course provided.

The pipe *B* is simply an ordinary steam-pipe for conveying the steam from the boiler to the renovator proper.

The steam-space *C* is preferably a rectangular sheet-metal box extending entirely over the bottom of the renovator and forming a floor for its lower chamber, *H*, into which heat 55 is radiated therefrom, thus converting said chamber into a dry-kiln for drying the feathers after they are steamed.

The pipe *D* is simply another ordinary steam-pipe for conveying the steam from the space 60 *C* to the perforated pipes *E E* above the partition dividing the kiln-chamber from the upper or steaming chamber.

The pipes *E E* are steam-pipes, having fine perforations distributed throughout their entire length, through which the steam escapes in all directions into the feathers, which are placed upon and about them in the steaming-chamber *G*.

The sliding partition *F* is simply a floor or 70 platform resting on slides *f*, which divides the apparatus into two chambers, *G* and *H*, one of which, *G*, serves as a steaming-chamber and the other, *H*, as a dry-kiln or chamber. When this partition is pulled out, as indicated by the dotted lines in Fig. 4, the two chambers are thrown together, and the feathers in the upper chamber are precipitated into the lower upon the plate *c*, which constitutes the top of the steam-space *C*, and also serves 80 as the floor of said chamber.

The chamber *G* is simply a steaming-chamber for the feathers, which are introduced through the door *I* and rest upon and around the steam-pipes *E E*, which are preferably at 85 or near the bottom of said chamber.

The chamber *H*, as before stated, is, in effect, a dry-kiln, into which the feathers are precipitated (after being sufficiently steamed) from the steaming-chamber *G* by simply pulling out 90 the sliding partition *F*, and wherein they are thoroughly dried by the heat from the steam-box *C* and pipe *D*, after which they are removed through the door *K*. During the process of drying access is had to this kiln for the 95 purpose of properly stirring up the feathers through the door *J*.

The operation of my invention may be briefly recapitulated as follows: The feathers to be renovated are placed in the chamber *G*, where 100 they are subjected to a thorough steaming through the medium of the perforated steam-

pipes E E, said feathers being occasionally stirred up by the operator to insure a thorough treatment. When these feathers are sufficiently steamed the sliding partition F is pulled out, 5 precipitating them into the chamber H, where they are dried out by the heat from the steam-chamber C, the partition F being meanwhile replaced and another batch of feathers inserted in the chamber G, so that the steaming 10 and drying processes may be proceeding simultaneously. By the time the first batch is dried the second will be steamed, so that the first may be removed, the second precipitated into the drying-chamber, and a third introduced 15 into the steaming-chamber, thus keeping the apparatus continuously in use.

By the arrangement shown the same current of steam is utilized in steaming one batch of feathers that is used in drying another batch, 20 which is of course a considerable saving over the process wherein two separate currents are used.

Having thus fully described my said invention, what I claim as new, and desire to secure 25 by Letters Patent, is—

1. An apparatus for renovating feathers,

consisting essentially of a steam-boiler, a feather-receptacle divided into two compartments by a removable diaphragm, a steam-chamber forming one side of one compartment 30 of said receptacle, a steam-pipe leading from the boiler to said steam-chamber, another pipe leading from said chamber to the other compartment, where it connects with perforated tubes or pipes, and said pipes or tubes located 35 inside said compartment, all substantially as set forth.

2. The combination of two chambers, G H, separated by a removable partition, F, the removal of which precipitates the contents of one 40 chamber into the other, the boiler A, steam-chamber C, perforated pipes E, and connecting pipes, whereby the same current of steam can be utilized both in drying and steaming feathers at the same time, substantially as set forth. 45

In witness whereof I have hereunto set my hand and seal, at Aberdeen, Ohio, this 12th day of January, A. D. 1882.

JOHN W. BINGAMAN. [L. S.]

In presence of—

EDWARD E. PERRY,

J. L. HAWK.
